US0D1018258S

(12) **United States Design Patent** (10) Patent No.: **US D1,018,258 S**
(45) Date of Patent: ** Mar. 19, 2024

(54) **LED FILAMENT**

(71) Applicant: **Hangzhou SIJUNSI Technology Co., Ltd**, Hangzhou (CN)

(72) Inventors: **Tiehan Ge**, Hangzhou (CN); **Yong Wang**, Hangzhou (CN); **Junya Ge**, Hangzhou (CN)

(73) Assignee: **HANGZHOU SIJUNSI TECHNOLOGY CO., LTD**, Hangzhou (CN)

(**) Term: **15 Years**

(21) Appl. No.: **29/768,294**

(22) Filed: **Jan. 28, 2021**

(30) **Foreign Application Priority Data**

Aug. 6, 2020 (CN) 202030441915.2
(51) LOC (14) Cl. **26-04**
(52) U.S. Cl. **D26/2**

(57) **CLAIM**

The ornamental design for an LED filament, as shown and described.

DESCRIPTION

FIG. 1 is a front view of an LED filament in accordance with the present invention;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

1 Claim, 7 Drawing Sheets
